UNITED STATES PATENT OFFICE.

JOSEPH LENARD WALTON, OF PINOLE, CALIFORNIA.

PULPER.

No. 928,009.

Specification of Letters Patent.

Patented July 13, 1909.

Application filed July 5, 1907, Serial No. 382,375. Renewed May 25, 1909. Serial No. 498,373.

To all whom it may concern:

Be it known that I, JOSEPH LENARD WALTON, a citizen of the United States, residing at Pinole, in the county of Contra Costa and State of California, have invented certain new and useful Improvements in Pulpers; and I do hereby declare the following to be a full, clear, and exact description of the invention, such as will enable others skilled in the art to which it appertains to make and use the same.

My invention relates to new and useful improvements in pulpers and more particularly to that class adapted to be used in preparing gun cotton and my object is to provide a device of this class whereby the cellulose used as the body of the guncotton will be thoroughly disintegrated during the process of nitration.

20 A further object is to provide means for adjusting the parts of the pulping mechanism and a still further object is to provide means for removing the guncotton from the pulper when the same has been thoroughly nitrated.

25 Other objects and advantages will be hereinafter referred to and more particularly pointed out in the claims.

In the accompanying drawings which are made a part of this application, Figure 1 is a top plan view of my improved form of pulper complete. Fig. 2 is a side elevation thereof. Fig. 3 is a sectional view as seen on line 3—3, Fig. 2. Fig. 4 is a sectional view as seen on line 4—4, Fig. 1 and Fig. 5 is a plan view of a plate employed in connection with the device for pulping purposes.

It has been the custom heretofore in mixing the acids with the guncotton to employ 40 certain classes of jars or nitrating centrifugals and it has been found in employing this form of apparatus, that portions of the cotton will not become thoroughly saturated with the acids, thereby forming what is 45 known as low nitrates, which will result in decomposition and the powder so formed will not stand the heat test and to this end I have provided my improved form of pulper, which consists of a tank 1; which is preferably oblong and has curved end walls 2 and 3. A vertical partition 4 extends through the central portion of the tank and is of less length than the tank, to form passages 5 and 6 around the ends of the partition. Extending laterally through the central portion of the tank 1 is a shaft 7, on which is mounted a

drum 8, said drum being located between one side wall of the tank and the partition 4 and the periphery of the drum is provided with a plurality of blades 9, which are 60 adapted to coöperate with a plurality of ribs 10, carried by a plate 11, said plate and ribs being fixed to a raised portion 12 of the bottom of the tank and the plate and ribs thereon, are curved to conform to the peripheral surface of the drum 8. The shaft 7 is extended through slots 13 in the side walls of the tank and the partition 4 and the outer ends thereof are supported in bearings 14 which are in turn supported on the upper 70 ends of screws 15, said screws passing through ears 16 carried by the side walls of the tank and by this construction it will be seen that the drum 8 may be readily adjusted toward or from the ribs on the plate 75 11, thereby giving a finer or coarser granulation to the cellulose passing between the drum and the ribs.

In operation, a pre-determined quantity of a proper mixture of nitric and sulfuric acid is 80 introduced into the tank through any suitable form of feed pipe 17, after which the disintegrated material is introduced into the tank through an opening 18 and by rotating the drum in the direction indicated by the 85 arrow 19 in Fig. 4 of the drawing, said material will be passed between the blades on the periphery of the drum and the ribs on the plate 10, thereby thoroughly disintegrating the material while immersed in the acid. 90 The drum 8 traveling in the direction indicated, will agitate the acid and form a current from end to end of the tank, as indicated by the arrow 20 in Fig. 3 of the drawings.

The raised portion 12 of the bottom of the tank at the right of the drum 8, is elevated to a point co-incident to the depth of the acid in the tank and the disintegrated material after passing between the drum and plate is thrown over the elevated end 21 of the raised 100 portion 12 onto a grate 22, which is hingedly secured at one end immediately below the end 21, while the opposite end thereof is provided with an angular guard 23, so that the said material will be gathered on the grate 105 and held until such time as it is desired to remove the completed product. The free end of the grate 22 is also provided with an arm 24 to the free end of which is secured a rod 25, by which means the grate is raised or 110 lowered and by lowering the free end of the grate while the pulping process is being per-

formed, the disintegrated particles of the material will still remain immersed in the acid when deposited upon the grate 22 and after the pulping process is completed, the 5 grate 22 is elevated to a horizontal position and in alinement with the lower edge of a port 26 in one wall of the tank, said port being normally closed by means of a door 27, a spout 28 being secured to the outer wall of 10 the tank, so that the product may be more readily removed through the port.

The cellulose is introduced into the tank at a point between one of the walls of the tank and the partition 4 and adjacent the drum 8, 15 so that the cellulose will pass directly into engagement with the drum and as the grate retains the disintegrated particles, that portion of the fluid at the opposite side of the partition from that occupied by the drum 8 will be substantially free from the cellulose. 20 It will be seen that by causing the acid to travel from end to end of the tank, the material on the grate will be thoroughly saturated with the acid as the acid in passing over the 25 end 21 will engage the material on the grate with more or less force. The amount of acid employed depends upon the quantity of material placed in the tank and the stated proportion is substantially 75 pounds of the 30 acid to 1 pound of said material, and at the removal of each batch of the prepared guncotton from the acid mixture, a certain amount of the acid is removed therewith, thereby requiring the constant replenishing of the acid 35 mixture, which may be regulated by means of a glass gage 29, which is preferably secured to one side wall of the tank and has graduations thereon, whereby the amount of the acid in the tank may be readily ascertained. 40

The upper surface of the tank 1 is provided with suitable ventilators 30, through which fumes of the acid escape, while the opening 18 is provided with a lid 31 to prevent fumes from escaping through the opening. The cover of the tank 1 is also provided with a plurality of transparent sections 32 of glass, mica, or similar substance, so that a view of the interior of the tank 45 may be readily had. By this manner of mixing the material with the acid, it will be seen that disintegrated material will be thoroughly saturated with the acid, thereby obviating any possibility of decomposition 50 of the guncotton 55

The blades 9 and the ribs 10 are preferably constructed of metal, so that they will not become easily broken and will thoroughly separate the particles of cellulose passed between the drum and plate, and the ribs 10 are 60 inclined from the central portion of the plate 11 to the outer edge thereof, thereby forming said ribs substantially V-shaped.

What I claim is:

1. A pulping engine of the character described, comprising a tank having a mid-feather, a suitably driven drum equipped with perimetric radial blades, a plurality of ribs arranged below said drum, a concaved upraised member arranged under said drum 70 and equipped with said ribs, and a grate hinged or pivoted at one end to said upraised member at its delivery end, the opposite end of said grate being suspended from, and having connected thereto an adjusting 75 screw-threaded member working in a fixed screw-threaded sleeve.

2. In a device as described, a tank having a longitudinal central partition therein with its ends arranged short distances from the 80 ends of said tank, a suitably driven drum having radial perimetric ribs thereon and a concaved up-raised portion in the bottom of said tank equipped with a series of ribs adapted for coaction with the ribs on said 85 drum, a grate having one end pivoted at the delivery end of said up-raised portion, and an adjusting means for controlling the disposition of said grate.

3. In a device as described, a tank having 90 arranged therein a longitudinal central partition with its ends stopping at short intervals from the ends of said tank, a suitably driven drum equipped with a series of radial ribs, a concaved up-raised portion arranged 95 in said tank, below said drum and provided with a series of ribs adapted for coöperation with said drum, a grate hinged at the delivering end of said raised portion and provided with an upstanding guard, and an adjusting screw pivotally connected to the 100 outer end of said grate.

In testimony whereof I have signed my name to this specification in the presence of two subscribing witnesses.

JOSEPH LENARD WALTON.
